UNITED STATES PATENT OFFICE.

FRANK VALLERY, OF BELWOOD, ONTARIO, CANADA.

SKATE-DRESSING TOOL.

Application filed August 28, 1926, Serial No. 132,212, and in Canada February 19, 1926.

Skates are generally ground upon a rotating emery wheel or the like, but the wheel is generally of comparatively coarse material and consequently the blade of the skate is 5 left more or less rough. My object therefore is to devise a tool by means of which this roughness may be smoothed off without danger of taking off the sharp edge which it is so desirable to retain.

10 I attain my object by means of the constructions hereinafter described and illustrated in the accompanying drawings in which

15 Fig. 1 is a front view of my device; and Fig. 2 an end view of the same.

In the drawings like numerals of reference indicate corresponding parts in the different figures.

20 My device comprises a U-shaped frame, usually bent up from a sheet of flat metal. Between the legs 1 of the frame is positioned a spacer 2, which is usually a little less in thickness than the thickness of the skate blade to be dressed. Wrapped around this spacer 25 is one or more plies 3 of sand paper or emery cloth. The spacer and the abrading material carried thereby are held in place by means of a bolt 4 by means of which the legs 1 are drawn together to frictionally hold the 30 spacer and abrading material in position. As skate blades usually have their greatest thickness right at the lower edge, and gradually decrease in thickness towards the plates by means of which the skates are 35 secured to the shoe, the spacer 2 will also preferably be similarly shaped.

It will be noted that the lower edge of the spacer 2 is somewhat back from the ends of the legs 1, so that the extending ends of the 40 legs form guides which engage the sides of the blade to prevent sidewise movement of the device. The device is thus held in proper alignment with the blade of the skate, and there is therefore little danger 45 of the device tilting to one side and therefore acting more on one side of the blade than the other.

The device is used by placing the same with the legs 1 straddling the blade and the 50 abrasive material in engagement with the blade. The device is then moved back and forth longitudinally of the blade until the blade has been given the desired surface.

To remove any burring, which may be 55 formed on the sides of the blade, I provide

on one of the legs 1 a piece 5 of abrading material as indicated.

If the blade of the skate to be dressed is of greater thickness than the spacer, and abrading cloth, it will be apparent that one or more plies of suitable material may be wrapped around the spacer bar to give the necessary thickness to permit the skate to enter the space between the guides.

The frame 1 will usually be made of 60 spring material so that the legs normally tend to move apart.

The bolt 4 will be provided with a square neck, and one of the legs 1 will be provided with a similarly shaped hole. The nut 70 may therefore be tightened up without danger of the bolt also turning.

While the device is intended particularly as a dressing tool and not as a sharpening 75 tool, it will of course be evident that once the blade has been well ground on a grinding wheel, it would not be difficult to keep a good edge on the blade for a considerable time by means of my device.

From the above description it will be seen 80 that I have devised a construction which will satisfactorily attain the object of my invention as set out in this specification.

It will be noted on reference to the drawing that the spacer 2 is tapered from end to end. This facilitates the taking up of any slack which might otherwise exist in that portion of the abrading material 3 which engages the skate. The abrading material and spacer are positioned with the upper edge of the spacer engaging the bolt 4, but with the spacer extensions more to one side as indicated in dotted lines. The nut on the bolt 4 is then tightened up so that the abrading material is frictionally held 95 between the spacer and the frame 1. The spacer is then driven up to the position shown in full lines to take up any slack which may be in the abrading material.

What I claim is:

1. In a skate dressing tool the combination of a U-shaped frame adapted to straddle the blade of the skate; a spacer bar between the legs of said frame, but spaced from the ends of the legs; abrading means carried by 105 said spacing bar; and a bolt for drawing the legs towards one another to clamp the spacer bar and abrading means in position, the upper edge of the spacer bar being tapered longitudinally and adapted to be 110

wedged against said bolt to tighten the abrading means on the spacer.

2. In a skate dressing tool for use with skates having blades that taper away from the skating surfaces, the combination of a U-shaped frame adapted to straddle the tapering blade of the skate; a spacer bar between the legs of said frame but spaced from the ends of the legs, said spacer bar being tapered transversely thereof to correspond to the tapering blade, having its greatest thickness towards the bottom of the U-shaped frame; abrading means carried by said spacer bar; and means for drawing the legs towards one another to clamp the spacer bar and abrading means in position.

3. In a skate dressing tool for use with skates having blades that taper away from the skating surfaces, the combination of a

U-shaped frame adapted to straddle the tapering blade of the skate; a spacer bar between the legs of said frame but spaced from the ends of the legs, said spacer bar being tapered transversely thereof to correspond to the tapering blade, having its greatest thickness towards the bottom of the U-shaped frame; abrading means carried by said spacer bar; and a bolt for drawing the legs towards one another to clamp the spacer bar and abrading means in position, the upper edge of the spacer bar being tapered longitudinally and adapted to be wedged against said bolt to tighten the abrading means on the spacer.

Signed at Hamilton, Ont., Canada, this 23rd day of August, 1926.

FRANK VALLERY.
